UNITED STATES PATENT OFFICE.

ALBERT J. HANSON, OF ARLINGTON, MASSACHUSETTS, ASSIGNOR TO AMERICAN METALLURGICAL CORPORATION, OF BOSTON, MASSACHUSETTS, A CORPORATION OF MASSACHUSETTS.

POT FURNACE.

Application filed November 9, 1927. Serial No. 232,036.

This invention relates to pot furnaces more especially to those which are electrically heated. Such furnaces are commonly used in the heat treatment of metal articles, the pot containing a molten bath such as of cyanide into which the articles to be treated are immersed for a time. During the immersion and removal of the articles, the bath material is spattered or drips more or less on the rim of 10 the pot and the top of the furnace, from which it is liable to pass into the furnace outside of the pot and cause great damage to the resistor heating units with which it may come in contact in view of its corrosive nature, particularly when contacting with the highly heated resistors.

In accordance with the present invention, therefore, the upper margin of the pot and cooperating parts at the top of the furnace are 20 so constructed as to be effectual in preventing access of the bath material to the furnace interior. To this end the pot is provided with an out-turned marginal lip at its top presenting a plurality of flanges or ridges with which 25 a complementally formed top member of the furnace engages. Preferably also the parts are so formed that the top furnace member extends over the marginal lip and engages the pot below its upper edge so that any material 30 dripping on the furnace top is directed into the pot below its top and is prevented from finding its way into the furnace outside of the pot. As a further precaution the joint between the furnace top member and the pot 35 may be sealed with a resistant cement. If desired also, the outer edge of the furnace top plate may be provided with one or more downwardly extending annular flanges co-operating with similar upwardly extending 40 flanges of an outer top plate or portion of the furnace.

For a more complete understanding of this invention, reference may be had to the accompanying drawings in which

45 Figure 1 is a side elevation of a pot furnace constructed according to this invention.

Figure 2 is a fragmentary section on line 2—2 of Figure 1.

50 As best illustrated in Figure 2, the pot 1 is formed at its upper end with an outwardly extending marginal rim portion 2 provided with a plurality of vertically upwardly extending annular flanges 3 and 4, the flange 4 being at the extreme outer end of this portion

and constituting in effect its upturned edge. 55 As shown also this marginal portion is provided with a vertically downwardly extending annular flange 5. The pot itself projects downwardly within a pot-receiving opening 6 in the furnace. The furnace is provided with a firebrick lining portion 7 directly surrounding the pot-receiving opening 6 outwardly of which is positioned monolithic insulating material 8 which is surrounded by one or more layers of insulating brick 9, the whole being enclosed within a metal casing 10. The annular flange 5 of the pot margin may be seated outwardly of an upstanding inner marginal flange 12 of an annular plate 13. This plate 13 may well be of a heat resistant 70 alloy and is covered over by means of an insulating layer 14 also of annular form within the opening 15 which is shaped to conform to the outer and lower edges of the portion 2 of the pot. This covering 14 may if desired be 75 formed in plastic condition so as to make a close fit within the pot and with the plate 13 defines an annular groove within which the flange 5 of the pot engages. On the upper face of this portion 14 is shown an annular plate 16 which may be of a heat resistant alloy, or if the heat is not to be too great, of cast iron. This plate 16 has a downwardly turned flange 17 which engages over the flange 3 of the pot and contacts with the pot 85 beneath its upper edge. It may also have another annular downwardly directed flange 18 which nests between the flanges 3 and 4 and is formed substantially complemental thereto. Any space between them may be 90 filled with a suitable resistant cementitious material so as to seal the parts together, thus preventing as far as possible the passage of bath material therebetween by capillary or other action. This double seal with the top 95 plate 16 engaging over the margin of the pot and contacting with the pot beneath its upper edge is quite effective for the purpose.

Particularly where the plate 16 is formed of alloy there may be positioned outwardly 100 thereof a second annular cover plate 20 formed of cast iron or the like, this being cheaper than the alloy and being effective where the higher temperatures are not present. As shown this plate 20 may have a pair 105 of upwardly directed annular flange portions 21 and 22 with which cooperate in nesting relation downwardly directed annular

flange portions 23 and 24 on the outer edge of the annular plate 16. These parts are formed substantially complementary and may be sealed together by means of resistant cementitious material. The outer marginal portion of the plate 20 may be turned downwardly as at 25 to embrace the metal casing 10. Any bath material which drips on the top of the furnace is therefore either directed back into the 10 pot beneath its upper edge or flows outwardly away from the pot opening, the parts being so sealed that access of this material to the interior of the furnace outside of the pot where it might contact with the resistor elements is effectually prevented.

Having thus described an embodiment of this invention, it will be evident to those skilled in the art that various changes and modifications might be made therein without departing from the spirit or scope of the invention.

I claim:

1. In combination, a furnace having a pot-receiving opening, a pot in said opening having an upper marginal portion extending outwardly in position to overlie a portion of said furnace, and an annular furnace plate engaging over said marginal portion and extending below its upper edge.
2. In combination, a furnace having a pot-receiving opening, a pot in said opening having an upper outwardly directed marginal portion arranged to overlie a top portion of

said furnace, said marginal portion having a plurality of concentrically arranged flanges 35 projecting vertically therefrom, and an annular furnace plate having a plurality of concentrically arranged flanges with which the flanges of said marginal portion nest.

3. In combination, a furnace having a pot-receiving opening, a pot in said opening having an upper outwardly directed marginal rim, an annular flange projecting from the lower face of said rim and engaging in an annular groove in said furnace about said opening, said rim having an upturned outer edge, and an annular plate supported on the top of said furnace and having a downturned inner margin engaging said pot within said upturned edge.

4. In combination, a furnace having a pot-receiving opening, a pot in said opening having an outwardly directed marginal flange, an outer annular plate on the top of said furnace, an inner annular plate on the top 55 of said furnace, the outer edge of said inner plate being sealed to the inner edge portion of said outer plate, and said marginal flange being sealed to the inner edge portion of said inner plate, each of said seals comprising a plurality of interfitting flanges and channels and cementitious material therebetween.

In testimony whereof I have affixed my signature.

ALBERT J. HANSON.
